CLYDE S. TOMPKINS, OF ROSEDALE, KANSAS.

TOBACCO-BOX ATTACHMENT.

1,279,946.

Specification of Letters Patent. Patented Sept. 24, 1918.

Application filed April 27, 1918. Serial No. 231,187.

To all whom it may concern:

Be it known that I, CLYDE S. TOMPKINS, a citizen of the United States, residing at Rosedale, in the county of Wyandotte and State of Kansas, have invented a new and useful Tobacco-Box Attachment, of which the following is a specification.

This invention relates to tobacco box attachments.

10 The object is to provide an attachment for the lids of ordinary tobacco boxes, such as are in common use, whereby a plurality of cigarette papers, peculiarly folded, are held within the said lid in such manner as to be easily extracted therefrom, one at a time, as desired, for use in making cigarettes.

20 A further object is to provide such an attachment, constructed in a simple manner and permanently secured to the under side of a tobacco box lid and capable of holding a sufficient number of superimposed folded papers to consume the entire box full of tobacco in making cigarettes, the said papers being so folded and held within the lid as to permit of the top one being readily extracted, and by such operation, causing the edge of the next paper to be presented outside of the holding means for extraction, in turn.

30 A full and complete understanding of the invention may be obtained from the following detailed description, taken in connection with the accompanying drawing forming a part of this specification; it being understood that while the drawing shows a practical form of the invention, the latter is not confined to strict conformity therewith, but may be changed or modified, so long as such changes or modifications mark no material departure from the salient features of the invention, as specifically pointed out in the appended claim.

In the drawing, in which like reference characters designate similar parts throughout the several figures:

Figure 1 is a perspective view of an ordinary tobacco box, the lid being shown opened and having the improved paper holder attached thereto.

50 Fig. 2 is an enlarged vertical, longitudinal sectional view of the upper portion of the same, the lid being shown closed.

Fig. 3 is a transverse sectional view on a greatly enlarged scale of the lid in open position, the upper portion of the box being shown in elevation, the cigarette papers be-

ing reduced in number and greatly exaggerated in thickness and spacing, in order to render the illustration thereof more easily understood.

Since the exact structure of the tobacco box proper forms no part of the present application, an ordinary box 1, of a well-known type, has been illustrated, said box having the usual hinged lid 2, secured at its open end and provided with the customary downwardly extending flange 3 provided on its marginal edges and adapted to embrace the upper end of the box, when closed.

The flange 3, on the ordinary tobacco box, is of considerable depth, in order to more effectually exclude air and thus maintain the tobacco within the box, in the desired condition, and also, by reason of its frictional engagement with the box, to prevent the accidental opening of the lid. Thus ample room is to be found within the lid of the average tobacco box, as found on the market at the present time, for the application of the attachment about to be described, so that the same may perform its function, without interfering with the contents of the box, even when the latter is properly packed to its full capacity, as it comes from the factory.

For the purpose of supporting the cigarette papers, as hereinbefore specified, within the lid 2 of the box 1, a metallic spring clip is secured longitudinally of the lid, upon the under side thereof. The clip is formed of a strip of spring metal of sufficient strength to exert a clamping action upon the pack of folded papers and to continue such pressure until the last of the pack of papers has been removed.

The said metallic strip is considerably less in width than the width of the box lid 2 and, when bent into shape, is of a length to easily fit between the ends of the lid and to be secured thereto in a manner to be described. The strip is bent to form terminal foot portions 4, which are appropriately perforated for the reception of suitable rivets 5 which also traverse proper perforations formed in the lid, adjacent to its ends, and are upset in the ordinary manner to rigidly secure the attachment in place.

Adjacent to the rivets 5, the metallic strip is bent outwardly, or offset away from the lid 2 to form arms as indicated at 6 in the drawing, and the intermediate portion 7 of the said strip, between the outwardly

bent arms, is depressed or bent toward the said lid, thus providing bowed spring portions 8, the tendency of which is to exert a constant pressure upon the intermediate portion of the strip toward the lid 2.

The ordinary cigarette paper is substantially twice as long as it is wide, and in the present instance, they are adapted to be folded transversely, in a certain manner, 10 having interlocking parts, and placed between the intermediate portion 7 of the spring clip and the underside of the lid 2, the distance between the outstanding arms 6 being somewhat greater than the width 15 of the cigarette papers.

As illustrated in Fig. 3 of the drawing, on an exaggerated scale, each paper 9 is transversely folded, at *a*, *b* and *c*, respectively. The fold *a* is located adjacent to 20 the upper or outer end of the paper, when the box lid is in open position, thus providing a portion *d* which lies outside of the spring clip and consequently exposed and in a position to be readily taken hold of 25 for removal. The folds *b* and *c* are so located, with respect to the length of the paper, as to provide three even plies or 30 lengths thereof, *e*, *f* and *g*, which when folded are slightly less in length than the width of the box lid, as shown in Fig. 3 of the drawing.

The inner or bottom portion *g* of each strip of paper is adapted to underlie the upper or outer portion *e* of the next or following strip, so that, when the outermost strip is pulled by the user, the fold *c*, thereof, will tend to bind on the fold *a* of the

following strip and, rolling the same upon itself, will extract it and cause it to assume the position of the uppermost strip, as shown 40 in Fig. 3, after the preceding strip is freed therefrom.

From the foregoing it will be seen that a simple device has been provided for holding cigarette papers within the lid of a 45 tobacco box, and that the same may be so cheaply constructed and secured in position upon the box, as to add no material cost to the manufacture thereof, and that the same may be made to hold a sufficient number 50 of papers in easy reach of the user, to use up the contents of the box.

What is claimed is—

In combination with the flanged lid of a 55 tobacco box, a cigarette paper holder comprising a metallic spring clip formed of a strip of metal narrower than the lid, but nearly of the same length, said strip being riveted at each terminal to the inner side 60 of the lid and adjacent to the ends thereof, and having outwardly bowed or offset 65 spring portions near the rivets, the remaining portion of the strip between the said bowed portions being depressed toward the lid for clamping and holding a pack of folded cigarette papers.

In testimony that I claim the foregoing as my own, I have hereto affixed my signature in the presence of two witnesses.

CLYDE S. TOMPKINS.
